United States Patent Office.

SOLOMON BROCK, OF BROOKLYN, NEW YORK.

Letters Patent No. 73,572, dated January 21, 1868.

IMPROVEMENT IN PAPER-FILES.

The Schedule referred to in these Letters Patent and making part of the same.

TO ALL WHOM IT MAY CONCERN:

Be it known that I, SOLOMON BROCK, of the city of Brooklyn, in the county of Kings, and State of New York, have made certain new and useful Improvements in Letter and Paper-Files; and I do hereby declare that the following is a full, clear, and exact description of the same, reference being had to the accompanying drawings, making part of this specification, in which—

- Figure 1 represents a full view of my file as used for filing letters in book-like form.
- Figure 2 is a vertical section across of the same.
- Figure 3 is a longitudinal section through the back of the same.
- Figure 4 is a perspective view of a bundle of letters filed and secured together, and ready to be stored away.
- Figure 5 is a perspective view of a modification of my file, as constructed when used for filing newspapers.
- Figure 6 represents a modification of my letter-file, showing a front view of it, and constructed with metallic springs to operate the paper-flap, and having a spring-catch on it to hold the flap when in position to insert the letter.
- Figure 7 is a vertical central, and
- Figure 8 a cross-section of the same.
- Figure 9 is an end view of the same.
- Figure 10 is a perspective view of a bundle of letters collected and removed from the file, and partly tied to be stored away.

Similar letters of reference indicate corresponding parts in the several figures.

The nature of my invention consists, first, in the employment of needles or file-hooks, which are straight, combined with a sliding paper-flap working over the needles, and having the side of the file-back, to which the needles are attached, hinged or otherwise made movable, so as to change the position of the needles so that ready access is had to remove the papers filed in one bundle, whereby the papers filed can be removed in good order, with readiness and dispatch, without mixing or disturbing the same; second, it consists in providing the needles or file-hooks of letter and other files with eyes in the ends of them, like eyes in sewing-needles, whereby the papers filed upon the same are at once collected on a thread which has been previously drawn through the eyes, and thereby such papers can be bound book-like, or attached firmly together.

To enable others skilled in the art to make and use my invention, I will proceed to describe its construction and operation.

A, figs. 1, 2, 3, 6, 7, 8, and 9, represents the file-case as ordinarily constructed in book-like form, but made of sheet metal, with a rounded back, and with straight sides. The side, B, is loosely attached or hinged to the ends of the case A. C C are slots, in which the paper-flap D is guided. They may be made in the ends of the case, as shown in figs. 1, 2, and 3, or in a separate partition, and also in the ends, as shown in figs. 6, 7, 8, and 9, so that the said paper-flap will freely slide from the side, B, to its opposite side of the said case. To the side, B, I secure straight needles E E E, at proper distances apart, and at right angles from the side, B, to the opposite one; and I make the paper-flap with corresponding openings or holes in it to allow the flap to pass freely over the needles. F F represent springs, which may be made of rubber, as shown in figs. 1, 2, and 3, or of metal, as shown in figs. 6, 7, 8, and 9. They are made and secured in a manner so as to draw the flap to the side, B, but admit of being pressed back by means of the operator taking hold of the flaps and forcing it over from the side, B, to the opposite side. In order to allow the insertion of a letter to be filed, or of the papers filed to be removed, I either employ a small notch, H, in the ends of the slots C C, as shown in figs. 2 and 5, or a spring-catch, H', shown in figs. 6 and 8, so that by pressing the flaps a little upwards, it will hook fast in the said notch H, or that by pressing the flaps beyond the spring-catch H', the catch will spring in front of the flaps, as shown in red lines in fig. 8.

When the file is used, the needles E E are threaded, the flap is forced to stop, as stated, in the notch H'. Now the paper to be filed is inserted between the flap and the points of the needles. The flap is then pressed out of the notch H, or the catch pressed down from the flap. The flap being now relieved, the springs F F force it and the paper filed over the needles, against the side, B. After a bundle of papers has been on the file, and it is desirable to remove the same for making room for new ones, the operator forces the flap again off the

needles, and while held by the notch H or catch H', the side, B, is turned in horizontal position out off the case A, as shown in fig. 9, in dotted lines. The cord or thread is now partly withdrawn from the papers, so that only a single thread is left in the papers, which is also withdrawn from the needles E, as shown at x x, in fig. 10, and the ends of the thread are firmly tied together, as shown at y y, in fig. 10, and the package of papers can be safely taken from the file and stored away, being secured together in book-like form, as shown in fig. 4. Instead of constructing the file of sheet metal, and with the slots C C, it may be made of wood combined with wire guides on its ends, as shown in fig. 5, and may be manufactured for filing newspapers at small expense.

From the foregoing it will be seen that files constructed and provided as herein shown, are of little expense and of great utility.

What I claim as my invention, and desire to secure by Letters Patent, is—

1. The employment of threaded needles, arranged stationary in the file, and operating with a paper-flap, for the purpose of passing a thread in the letters or papers, with the operation of filing the same in the file, so that the letters or papers may thereby be secured when removed from the file, substantially as herein shown and described.

2. The combination and arrangement of the file-case or frame A with the side, B, and needles E E, the flap D, and springs F F, and notches H H, operating together substantially as and for the purpose herein shown.

SOLOMON BROCK.
